UNITED STATES PATENT OFFICE.

CHARLES A. EVARTS, OF MERIDEN, CONNECTICUT, ASSIGNOR TO THE BRADLEY & HUBBARD MANUFACTURING COMPANY, OF SAME PLACE.

DESIGN FOR A LAMP-BURNER.

SPECIFICATION forming part of Design No. 18,202, dated March 27, 1888.

Application filed February 27, 1888. Serial No. 265,523. Term of patent 7 years.

To all whom it may concern:

Be it known that I, CHARLES A. EVARTS, of Meriden, in the county of New Haven and State of Connecticut, have invented a new 5 Design for Lamp-Burners; and I do hereby declare the following, when taken in connection with accompanying drawing and the letters of reference marked thereon, to be a full, clear, and exact description of the same, and 10 which said drawing constitutes part of this specification, and represents a side view of the burner complete.

This invention relates to a design for the burner for that class of lamps which employ a 15 tubular wick; and it consists in the configuration or exterior shape of the body of the burner, as shown in the accompanying illustration. The base portion *a* of the burner is of cylindrical shape. Around the upper edge of the 20 base is the representation of an annular bead, *b*. From this bead the surface rises, but ex-

pands in an outwardly curved shape to its upper edge, terminating in the representation of a bead, *d*, above which is the chimney-rest *e*, contracted from the diameter of the bead and 25 of cylindrical shape. It is to the peculiar shape of the body or air-distributing portion of the burner that the design particularly relates.

I claim—

The design for a lamp-burner, consisting of 30 the cylindrical base *a*, the representation of an annular bead, *b*, above the base, the body expanding in an outward curve and terminating at its upper edge in the representation of an 35 annular bead, *d*, and the chimney-rest above, of smaller diameter and of cylindrical shape, as shown in the accompanying illustration.

CHARLES A. EVARTS.
